UNITED STATES PATENT OFFICE.

JOHN BOOTHMAN, OF NEW BEDFORD, MASSACHUSETTS, ASSIGNOR OF ONE-HALF TO WILLIAM B. WOOD, OF SAME PLACE.

SHUTTER-FASTENER.

SPECIFICATION forming part of Letters Patent No. 601,546, dated March 29, 1898.

Application filed February 16, 1897. Renewed February 11, 1898. Serial No. 669,977. (No model.)

To all whom it may concern:

Be it known that I, JOHN BOOTHMAN, a citizen of the United States, residing at New Bedford, in the county of Bristol and State of Massachusetts, have invented certain new and useful Improvements in Window-Blind Fasteners; and I do hereby declare the following to be a full, clear, and exact description of the invention, such as will enable others skilled in the art to which it appertains to make and use the same.

This invention relates to certain new and useful improvements in devices for holding blinds and shutters open or closed; and it has for its objects, among others, to provide a simple and cheap device readily attached to shutters now in use and which will serve to effectually hold the shutter in either its open or closed position and yet readily operated to open the shutter when closed, or vice versa.

The device is not uncomely in its appearance, and as it can be manufactured at a trifling cost it will be brought within the reach of all.

Other objects and advantages of the invention will hereinafter appear, and the novel features thereof will be specifically defined by the appended claims.

The invention is clearly illustrated in the accompanying drawings, which, with the letters of reference marked thereon, form a part of this specification, and in which—

Figure 1 is a perspective view showing one shutter open and the other closed. Fig. 2 is a detail on an enlarged scale, showing the parts which are attached to the shutter. Fig. 3 is a section through the pivot of the swivelled arm.

Like letters of reference indicate like parts throughout the different views.

Referring now to the details of the drawings by letter, A designates a portion of the window-frame, and B the shutter or blind, hung to swing in the usual manner.

On the inner face of the shutter or blind, near the lower edge thereof, is secured the plate C, the outer vertical edge of which is provided with the right-angled portion D, which is provided with a vertical slot E, open at its upper end, while on this right-angled

portion is the latch F, which is adapted to be moved back into a groove or recess G, formed in the plate C, as shown. This latch serves to prevent accidental displacement of the locking-arm when the latter is in the said slot.

H is the locking-arm. It is slightly curved near its outer end to enable it to be engaged in the said slot, and its inner end is bent to go around a pivot-pin and form an eye, which works upon the said pin as upon a pivot. This pin I is held in the ears or lugs I', which project outward from the plate J, which is mounted to swivel on the plate C, as shown. It will thus be seen that the locking-arm has a movement as upon a pivot and also upon a swivel, in order that it may assume the different positions necessary to perform its proper functions. This locking-arm is provided near its outer end with a hole K, for a purpose which will soon appear.

M are pins on the window-sill, over which the holes in the locking-arms engage to hold the shutters in their closed position.

L are hooked arms secured on the outside of the building and which are designed to be engaged by the locking-arms to hold the shutters open.

The operation will be apparent. The shutters are locked after being closed by simply engaging the openings in the locking-arms over the pins M. When opening the shutters, the arms are disengaged from the said pins and placed in the slots of the right-angled portions of the plates C, where they will be held by the latches, and when the shutter is thrown open against the wall of the building the locking-arms are engaged by the hooked arms or latches L and the shutter locked.

It will also be noted that by my construction the shutter cannot be opened from the outside.

Modifications in detail may be resorted to without departing from the spirit of the invention or sacrificing any of its advantages.

What is claimed as new is—

1. The combination with the plate having a right-angled portion with vertical slot open at its upper end, of a locking-arm mounted on

said plate for pivotal movement, and a swiv-
eled plate carrying the pivot on which the
locking-arm works, as set forth.

2. The combination with the plate having
5 a right-angled portion with open-ended slot,
and a latch, of the locking-arm mounted on
said plate for pivotal and swivel movements,
as set forth.

3. The combination with a shutter, of a
10 plate secured thereto and provided with a
right-angled portion with open-ended slot,
and a latch parallel therewith, a plate swiv-

eled on said plate and having ears, a pin held
in said ears, and a locking-arm mounted on
said pin and provided with a curved portion 15
and a hole, all substantially as shown and
described.

In testimony whereof I have signed this
specification in the presence of two subscrib-
ing witnesses.

JOHN BOOTHMAN.
